ALTERNATING-CURRENT WELDER

Leroy F. Kingery, Stockton, Calif., assignor of
one-half to Hickinbotham Bros., Ltd., Stockton,
Calif., a corporation of California

Application January 2, 1940, Serial No. 312,004

5 Claims. (Cl. 171—119)

This invention relates in general to electric welding apparatus, and in particular the invention is directed to an improved electric welder of the A. C. type.

The principal object of the present invention is to provide an A. C. welder including mechanism designed to effect a stabilization of the welding arc; such mechanism including a secondary coil flexibly mounted in relation to the primary coil.

Another object of the invention is to provide simplified means for readily moving the secondary coil relative to the primary coil, and to maintain the coils in any relative or adjusted position.

A further object of the invention is to provide an A. C. welder characterized by its perfection of current control, and by its relatively great range of current values; the range being extended much farther in the lower current values than is ordinarily accomplished.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a front elevation of the improved welder.

Figure 2 is an enlarged back elevation of the welder, the housing or case being in section.

Figure 3 is a transverse section on line 3—3 of Fig. 2.

Figure 4 is a sectional plan on line 4—4 of Fig. 2.

Referring now more particularly to the characters of reference on the drawings, the device includes a transformer assembly which comprises a laminated, rectangular elongated core 1 disposed in upstanding position; said core including a central leg 2. Wooden side rails or clamps 3 are secured on opposite sides of the bottom horizontal portion 4 of core 1 and extend to and are connected with the sides of a housing or case 5 which encloses the transformer and related mechanism. Outwardly facing lengths of angle iron 6 are secured on and parallel to the upper horizontal portion 1 of the core, and such angle irons also are connected at their ends on the case adjacent its upper end and immediately be-

low its removable lid 8. By means of rails 3 and angle irons 6, the core is rigidly secured in case 5. The case is supported on casters 9 to facilitate movement of the device from place to place.

5. The primary coil 10 of the transformer is of usual construction and is wound about the lower end portion of the leg 2 of core 1; such primary coil including leads 11 which extend upward to connection with spaced terminals 12 on a rectangular, dielectric terminal plate 13 surrounding leg 2 at its upper end but beneath core portion 1. Grommets 14 of dielectric material are fitted in the adjacent side of the case and are adapted to receive the current supply cables (not shown) leading to terminals 12.

As is customary, the secondary coil 15 is mounted for movement relative to the primary coil 10 and core leg 2; the secondary coil 15 being of the "honeycomb" type and in this structure 10 being arranged for vertical movement to and from a position encircling and overlapping the primary coil. The coil 15 includes vertical securing strips 16 adjacent the outside corners, and said strips 16 are connected with inwardly facing angle members 17 disposed vertically in the inside corners of the coil by means of insulated tie bolts 18. Strips 16 and angle members 17 are of dielectric material.

A shaft 19 extends transversely above angle 30 irons 6 and is rotatably supported by spaced bearing blocks 20 mounted on said angle irons; one of said bearing blocks including an adjustable friction sleeve or drag 21 whose adjustment is accomplished through the medium of a bolt 22. At one end the shaft projects through the front of case 5 and is provided with a crank 23. Flexible metallic cables 24 are secured in winding relation on shaft 19 at points beyond but adjacent bearing blocks 20; one of said cables

40 depending to one corner of the secondary coil, there passing through a pulley 25 on the coil and thence extending upwardly to a fixed connection adjacent the shaft. The other cable extends horizontally above plate 23 to a direction changing pulley 26 and then extends down through a pulley 27 on the opposite corner of the secondary coil and returns to a fixed connection adjacent pulley 26. The horizontal portion of said other cable is separated from possible 45 contact with terminals 12 by means of an overhanging shelf 28 mounted on the adjacent angle iron 6. With rotation of the crank 23 in one direction or the other, the secondary coil 15 is raised or lowered to any desired position relative to the primary coil 10, and when the crank is 50

released the secondary coil remains suspended in such position as friction sleeve 21 prevents rotation of shaft 19 under the influence of the weight of such secondary coil.

Vertical movement of the secondary coil is guided by means of vertical guide posts 29 of angle shape and dielectric material; such posts being four in number and extending upward from rails 3 to dielectric plate 13. These posts are slidably engaged in guided relation by members 17 on the secondary coil. By reason of such arrangement the secondary coil can move vertically without restriction but cannot shift laterally.

Metallic plates or shields 39 are secured between adjacent ones of the posts and extend upward from a point adjacent the upper end of the secondary coil; one opposed pair of these plates extending up to the horizontal plate 13, while the other opposed pair terminate short of plate 13 in order to assure proper ventilation about the portion of leg 2 within the plane of plates 39.

The secondary coil 15 is provided with leads 31 which extend from said coil to a pair of "plug in" connector terminals 32 on the front of the case 5 and to which the welding or outlet cables (not shown) are adapted to be connected. A pointer 33 is carried by the secondary coil and projects through a vertical slot 34 in the case; said pointer registering with a scale 35 on the front of the case adjacent slot 34. This scale reads in terms of welding heat or current.

In use, the secondary coil 15 is adjusted to a desired position relative to the primary coil 10 and as indicated by pointer 33 on scale 35. As the secondary coil is flexibly suspended by cables 24, such coil is free to move upward. When both the primary and secondary coils are energized, there exists a magnetic repulsion therebetween which raises the secondary coil upward a slight but nevertheless certain distance relative to the primary coil; such repulsion being stronger with a rise in the output current of the welder as when the distance between the electrode and the work is decreased. The above "floating" movement of the secondary coil due to such magnetic repulsion, tends to stabilize the welding arc by damping out violent fluctuations in the output current and which are the result of the operator's inability to maintain a constant distance between the electrode and the work.

The metal plates 39 serve as magnetic shields or screens which extend the current range of the welder into the lower current values, i. e. they enable the current to be reduced to a point much lower than with an ordinary welder. This result is accomplished by reason of the fact that the shields 39 increase the leakage reactance of the transformer when set for the lower current values. Also, the current in the secondary coil at the low current values induces eddy currents in the magnetic shields or screens 39, and which eddy currents in turn react on the current in the secondary coil and tend to assist the "floating" secondary coil in damping out violent fluctuations.

In order to assure proper ventilation through the case 5 and about the enclosed apparatus, the case may be formed with suitable vent openings or louvers.

From the foregoing description it will be readily seen that I have produced such a device

as substantially fulfills the objects of the invention as set forth herein.

While this specification sets forth in detail the present and preferred construction of the device, 5 still in practice such deviations from such detail may be resorted to as do not form a departure from the spirit of the invention, as defined by the appended claims.

Having thus described my invention, what I 10 claim as new and useful and desire to secure by Letters Patent is:

1. In an electric welder, a transformer including an elongated core, a primary coil wound about a portion only of the core, guide members 15 of substantial length extending parallel to the core and primary coil and spaced thereabout, a secondary coil surrounding the core and said members and cooperating with the latter for guided movement in a direction lengthwise of said core, a magnetic shield surrounding another portion of the core and supported by said members clear of the path of movement of the secondary coil, and means to move said secondary coil in said direction.
2. In an electric welder, a transformer including an elongated vertical core, a primary coil wound about a portion only of said core, vertical guide posts of dielectric material spaced about the core and primary coil and extending substantially the length of said core, a secondary coil surrounding said core and posts and cooperating with the exterior of the latter for guided movement in a direction lengthwise of said core, and a magnetic shield surrounding another portion of the core and supported by said posts in spaced relation to the core and in clearance relation to the path of movement of the secondary coil, and means to move said secondary coil in said direction.
3. A device as in claim 2 in which said shield comprises metallic plates disposed in substantially edge to edge relation and forming an enclosure about the core; the posts being inwardly facing angle members which symmetrically engage and are secured with adjacent edge portions of adjacent plates.
4. A device as in claim 2 in which the shield comprises metallic plates disposed in substantially edge to edge relation and forming an enclosure about the bore, said shield being above the primary coil and extending upward therefrom to the upper end of the core, a dielectric plate supported by said posts at their upper ends, terminals on said plate, and wires leading downward between the posts and shield and connecting with the primary coil.
5. A device as in claim 2 in which the shield comprises metallic plates disposed in substantially edge to edge relation and forming an enclosure about the bore, said shield being above the primary coil and extending upward therefrom to the upper end of the core, a dielectric plate supported by said posts at their upper ends, terminals on said plate, and wires leading downward between the posts and shield and connecting with the primary coil; said dielectric plate enclosing the area between said posts, and certain ones of the metallic plates terminating short thereof and of the primary coil whereby to allow of an upward circulation of air through said shield and about said other portion of the core.

LEROY F. KINGERY.
